UNITED STATES PATENT OFFICE.

JOSEPH H. GUNN, OF CORTLAND, NEW YORK.

ELECTRIC SIGNAL FOR RAILWAYS.

1,074,859.

Specification of Letters Patent.

Patented Oct. 7, 1913.

Application filed August 3, 1908. Serial No. 446,619.

To all whom it may concern:

Be it known that I, JOSEPH H. GUNN, a citizen of the United States, residing at Cortland, in the county of Cortland and 5 State of New York, have invented certain Improvements in Electric Signals for Railways, of which the following is a specification.

This invention is an improvement in electric signals, and relates more especially to signaling devices used in connection with railroad switches, and is especially adapted for use with the electric signal for railways set forth in my prior Patent No. 890,049, 15 dated June 9, 1908.

My present invention contemplates the provision of means by which signals will be set automatically at suitable points along the railway in case the railroad-switch is 20 open or the operating-lever thereof has been tampered with in any manner.

The invention further contemplates the application of the switch signals either in connection with or independently of the 25 emergency danger signals.

The following specification enters into a detail description of my invention, and what I claim as new and desire to secure by Letters-Patent is more specifically set 30 forth in the appended claim.

In the accompanying drawings, which form a part of this specification: Figure 1 is a diagrammatic view of the electric signaling system, arranged in accordance 35 with my present invention. Fig. 2 is a detail view of a form of switch-stand. Fig. 3 is a detail view of an electric switch mechanism employed in connection with an ordinary switch-stand. Fig. 4 is a vertical 40 sectional view of Fig. 3, taken at the left of the switch-operating arm. Fig. 5 is a detail end view of the switch-operating arm.

Like numerals of reference indicate like 45 parts in all the figures of the drawings.

In carrying out my invention I preferably employ the railroad-switch signaling apparatus, hereinafter described, in connection with the emergency danger signal 50 system shown and described in my aforementioned patent. In the present instance I have shown but one station, as A, which is provided with the electric switches 5 and 6 for closing the circuits to operate the 55 signals in either direction from said station,

the switch 5 operating the signals 5^a, and the switch 6 the signals 6^a.

In connection with the railroad-switch I employ signals 7, one of which is located adjoining the railroad-switch, as B, and others may be located along the railway in either or both directions from said railroad-switch. These signals may be in the form of ordinary electric lamps, preferably large, showing a red light, or in the form of signal 65 blades of the character set forth in my prior patent, and in each instance are operated by an electric current and through the intervention of an electric-switch. The electric-switch is arranged so as to be operated automatically when the lever of the switch-stand is operated to throw the railroad-switch, and one form of operating means is herein shown and now described.

The switch-stand in the present instance 75 comprises a supporting frame 8 having a vertical shaft 9 with a crank 10 at its lower end connected to the rod 11 extending to the switch-points, as is usual. The vertical shaft is operated by a lever 12, and is extended upwardly so as to operate an electric-switch, the latter comprising a switch lever or arm 13 adapted to engage the contact-point 14. The lever or arm 13 projects from a segment 15 and is actuated to complete the circuit by means of a spring 16 connected to one end of the segment and to a stationary part, as the support 24. The throw of the segment and switch-lever is limited by a stop-pin 17. The upper end of 80 the vertical shaft of the switch-stand is provided with an arm or lever 18 having a depending portion 19 which travels in a segmental slot 15^a of the aforesaid segment and is adapted to turn the segment and 85 electric-switch-lever so as to break the circuit, the electric connections being shown in Fig. 3. The depending portion 19 is beveled at one side so that when the vertical shaft carrying the arm 18 is lowered in locking the switch-lever the segment will be moved to open the electric-switch and when said shaft is raised, preliminary to throwing the railroad switch-lever, the segment will move to close the electric-switch, whereby the railroad-switch must be in locked position to maintain the electric-switch open. As also shown in this figure the parts are suitably insulated. The lever 12 is preferably of that type having a bent end which 100

110

engages between ears 20 on the switch-stand to provide for locking the lever in either position, and in the operation of this lever it is required to first raise the same. 5 As will be seen in raising the lever 12 the shaft 9 is also raised by reason of the cam-shaped rear end 21 of said lever bearing on the switch-stand, and the upward movement of the shaft will release the segment so that 10 the electric switch lever will be turned to close the electric circuit and operate the signals. Therefore, the initial operation of the lever 12 to open the railroad switch will cause the signals 7 to be displayed, and 15 the electric circuit will not be broken until the lever 12 is again located in closed locking position. Thus to cut out the electric signals, as 7, the railroad switch must be entirely closed and the operating-lever 12 20 must be in locked position.

The arrangement shown and described provides for displaying suitable signals when a railroad-switch is open, or even partly open, and if desired the connections or wiring 25 may be such that upon the operation of the lever 12 to open the railroad switch, the operation of the electric-switch 13 will also operate the danger signals 5^a and 6^a in both directions from the station A, to thereby 30 warn approaching trains that the switch is open.

As heretofore stated this signaling system may be employed in connection with the electric signal for railways set forth in my 35 prior patent, but I do not wish to limit my

present protection by such application, for it will be obvious that the signal device for railroad-switches, as herein shown and described, may be also used independently. 40

The electric-switch is located in the present instance on a cross-arm supported at the upper end of a pole, and is preferably covered and protected from the weather by means of a dome-shaped inclosing-case 25. 45

Having thus described my invention, what I claim as new and desire to secure by Letters Patent, is:—

In an electric signal for railways, the combination with a railroad switch and lever for operating the same, of a vertically 50 movable shaft to which the railroad switch and lever are connected, electric signals, a rotatable electric-switch controlling the latter, a spring connected to the electric-switch for moving the same to normally closed position, an arm connected to and projecting from the vertically movable shaft, and a depending portion on the arm beveled at one side to engage and move the electric-switch to open position when the shaft is 55 turned and lowered to close and lock the railroad switch, substantially as shown and described.

In testimony whereof I have signed my name to this specification in the presence of 60 two subscribing witnesses.

JOSEPH H. GUNN.
